UNITED STATES PATENT OFFICE.

THOMAS BEECHER, OF NEW HAVEN, CONNECTICUT, ASSIGNOR TO W. & E. T. FITCH, OF SAME PLACE.

SNAP-HOOK.

SPECIFICATION forming part of Letters Patent No. 282,257, dated July 31, 1883.

Application filed April 27, 1883. (No model.)

To all whom it may concern:

Be it known that I, THOMAS BEECHER, of New Haven, in the county of New Haven and State of Connecticut, have invented a new Improvement in Snap-Hooks; and I do hereby declare the following, when taken in connection with accompanying drawing and the letters of reference marked thereon, to be a full, clear, and exact description of the same, and which said drawing constitutes part of this specification, and represents a sectional side view.

This invention relates to an improvement in that class of snap-hooks in which the mouth is closed by a longitudinally-sliding bolt. In the usual construction of this class of hooks the body of the hook is made in the form of a barrel and the bolt arranged within the barrel, with a spring behind it to force it forward toward the end of the hook. Through the barrel is a slot through which a thumb-piece on the bolt plays.

In the manufacture of this class of hooks there is considerable difficulty in obtaining perfect castings, in that the barrel is required to be cored; but, at best, so imperfect is this coring that it is found necessary generally to bore out the barrel, and if the coring be so perfect as not to require boring the necessary treatment of the casting to acids leaves more or less of the acid in the barrel or spring-chamber, which quickly acts upon the spring introduced therein, so that the destruction of the spring is a very frequent occurrence due to this presence of acid. Again, the barrel forms a receptacle for dirt or foreign substances which may enter or work in through the slot, or through the opening which is necessarily left therein for water to escape.

The object of my invention is to overcome these difficulties; and it consists in the construction of the hook, as hereinafter described, and more particularly recited in the claim.

A is the body of the hook, at one end constructed with a loop, B, or other device, as a convenient means for attachment, and at the other turned upward and over to form the hook C.

D is an arm, starting from the loop end and extending forward in line with the ends of the hook and in a plane parallel with the back. On this arm a tubular sleeve, E, is arranged

so as to slide freely on the arm toward and from the end *a* of the hook, the arm D serving as a guide for the movement of the sleeve, directing it in such movement so that it stands in line with the nose of the hook, as shown. This sleeve is made hollow or tubular, and within the sleeve is a spring, F, resting one end against a shoulder, *d*, on the arm and the other against a shoulder, *e*, in the sleeve, the tendency of the spring being to force the sleeve toward the nose of the hook, yet yielding for the movement of the sleeve away from the nose to open the mouth of the hook, as seen in broken lines. 55 Preferably the nose of the hook is made with a slightly-projecting stud to enter that end of the sleeve, so as to form a support for that end of the sleeve when the hook is closed. The sleeve may be provided with a thumb-piece or projection, *f*, which will serve as a convenience in opening the hook. By this construction the body part of the hook is readily cast complete, requiring no further operation than that of tumbling. The sleeve is open at both ends, 60 and may readily be bored out, or it may be cast and cored. By this construction there is no opening exposed for the entrance of foreign substances to interfere with the working of the spring. As the sleeve fits closely upon the arm 65 D at one end and closely to the nose of the hook at the opposite end, all apertures to the spring-chamber are closed when the hook is in use.

Preferably I form a lug, *h*, on the inside of 70 the body of the hook extending toward the sleeve, to prevent the ring or whatever the hook may be attached to passing back beneath, and so as to interfere with the working of the 75 sleeve.

I claim—

The herein-described snap-hook, consisting of the body A, terminating in a hook at one end and a device for attaching the hook at the opposite end, an arm, D, extending forward in line with the nose of the hook, combined with the tubular sleeve E, arranged on the bar D, and a spring within said sleeve, the action of which is to force the sleeve toward the nose of the hook, substantially as described.

THOMAS BEECHER.
